UNITED STATES PATENT OFFICE.

PHILIP F. SCHAEFER, OF NEW YORK, N. Y., ASSIGNOR TO PATRICK J. GALLAGHER, OF SAME PLACE.

DESIGN FOR A PLATEAU-FRAME.

SPECIFICATION forming part of Design No. 24,421, dated June 25, 1895.

Application filed April 24, 1895. Serial No. 547,047. Term of patent 7 years.

To all whom it may concern:

Be it known that I, PHILIP F. SCHAEFER, of New York, in the county and State of New York, have invented and produced a new and original Design for a Plateau-Frame, of which the following is a full, clear, and exact description.

Reference is to be had to the accompanying drawings, forming a part of this specification, in which the figure represents a perspective view of a plateau having a frame embodying my new design.

The leading feature of my design consists of the body having spaced supports each in the form of an animal's head with an animal's

leg merging directly into the head, foliated ornamental work extending from each support and narrowing from the same to points between the supports.

The body is shown surmounted by a border comprising a band and a series of small figures emanating from the upper edge of said band.

I claim—

The design for a plateau frame herein shown and described.

PHILIP F. SCHAEFER.
